DESIGN FOR A DIAL SCALE

Lester D. Singleton, Rutland, Vt., assignor to The Howe Scale Company, a corporation of Vermont

Application June 10, 1946, Serial No. 130,573

Term of patent 14 years

(Cl. D52—10)

To all whom it may concern:

Be it known that I, Lester D. Singleton, a citizen of the United States, and a resident of Rutland, in the county of Rutland and State of Vermont, have invented a new, original, and ornamental Design for A Dial Scale, of which the following is a specification, reference being had to the accompanying drawings, forming part thereof and in which

Fig. 1 is a front perspective view of a dial scale, showing my new design,

Fig. 2 is a side elevational view of said design.

I claim:

The ornamental design for a dial scale, substantially as shown.

LESTER D. SINGLETON.
